UNITED STATES PATENT OFFICE.

FRANK J. SCHISLER, OF WINTHROP, MINNESOTA.

PEN.

Application filed February 4, 1926. Serial No. 86,002.

The invention relates to improvements in pens or "metal paint brushes" of the type used primarily for printing signs, wide nibs being provided to produce a wide line when the pen is moved in one direction and a relatively narrow line when moved in a transverse direction.

It is one object of the invention to provide a pen of the character described in which a novel provision is made for securing an upper, resilient nib to the body of the pen.

Other objects are to make unique provision for varying the tension with which the upper nib is held against the lower nib, and to provide a novel association of parts, whereby the upper nib may be adjusted forwardly or rearwardly to the most advantageous position.

Yet another aim is to provide a pen which will be rather simple and inexpensive, yet will be efficient and in every way desirable.

With the foregoing in view, the invention resides in the novel subject matter herein-after described and claimed, the description being supplemented by the accompanying drawings.

Figure 1 is a top plan view of the pen.

Figure 2 is a longitudinal sectional view on the plane of line 2-2 of Fig. 1, showing the upper nib held under full tension, against the lower nib.

Figure 3 is a side elevation partly broken away and in section, showing the manner in which the tension on the upper nib may be decreased.

Figures 4 and 5 are respectively a side elevation and a top plan view illustrating the manner in which two line-forming units may be carried by the same handle for use either one at a time or simultaneously.

Figure 6 is a longitudinal sectional view showing a different form of construction.

Figure 7 is a top plan view of the pen disclosed in Fig. 6.

Figure 8 is a top plan illustrating a still further form of construction.

Figure 9 is a plan view of the upper nib shown in Fig. 8.

Figure 10 is a plan view showing another form of nib which may be used.

Figure 11 is a lower side elevation showing the manner in which liquid feeding grooves may be formed in any desired portion or portions of the upper nib, if non-uniform feed-

ing of the ink or paint is to be produced for shading purposes.

In the form of construction disclosed in Figs. 1, 2 and 3, 12 designates a rigid body portion of the pen, having a trough-like front end portion 13 and a reservoir 14 behind and communicating with said trough-like portion to contain the ink or paint. The front end of the portion 13 forms a stationary lower nib 15, and the side walls 16 for said trough-like portion may well be continuations of the reservoir side walls.

The rear end of the body 12 is formed with a socket 17 in which the front end of the handle 18 is secured, the top 19 of said socket being flat and longitudinally disposed and having upstanding flanges 20 at its side edges, formed by continuations of the reservoir side walls. In the present showing, a bridge 21 extends between the upper edges of the flanges 20, over the front part of the socket portion 19, and a finger-operated screw 22 is threaded through this bridge, said screw having a plate 23 swiveled to its lower end.

Received between the side walls of the reservoir 14, the side walls 16 of the trough-like portion 13, and the flanges 20, is an upper, resilient, longitudinally disposed upwardly bowed nib 24, said nib comprising a strip of spring metal which is reinforced and stiffened from its rear end to a point spaced rearwardly from its front extremity, by longitudinal flanges 25 which may either be suitably secured to the edge portions of the spring metal strip, or may be formed by upwardly bending said edge portions. The front portion 26 of the nib 24 is free of any reinforcing means, so that it may readily yield.

The rear part of the nib 24 is receivable between the plate 23 and the socket portion 19, and under normal circumstances, that is before the screw 22 is appreciably tightened, said nib and said socket portion 19 converge rearwardly as shown in Fig. 3 to a point of contact which is at the rear end of the nib. The downwardly curved front portion 26 then rests on and turns downwardly in front of the stationary nib 15 as shown in Fig. 2. By tightening the screw 22, the stiffened body portion of the nib 24 may be forced downwardly, and the nib end 26 is gradually placed under greater tension as such tight-

ening is effected. Thus, the nib end 26 may be held against the stationary nib 15 with any adequate degree of tension, according to the work being done and the quality of the liquid used in the pen. Pressing of the front extremity of the nib end 26 against the paper or other surface upon which printing or the like is being done, causes said nib end to yield upwardly from the stationary nib 15, permitting the liquid to flow.

The nib 24, it will be observed, may be slid forwardly or rearwardly and thus adjusted to produce the best results, and for producing such adjustments as well as for easily removing and re-applying the nib when necessary, it is provided with an appropriate handle 27.

In Figs. 4 and 5, two pen units U and U' are shown, mounted upon a common handle 18'. The unit U is identical with the pen structure above described, the unit U' is pivoted to said unit U as indicated at 28, and an appropriate spring 29 normally swings said unit U' upwardly as shown in Fig. 4. When its use is desired, however, it may be swung downwardly against the action of the spring to the limit permitted by an appropriate stop 30. One of the units is preferably rather wide and the other comparatively narrow, so that spaced lines of different widths may be made with this form of construction.

In Figs. 6 and 7, a pen body 12^a is provided, having a relatively large and wide reservoir 14^a, said reservoir having a top 19^a extending forwardly a suitable distance into the trough-like front portion of the aforesaid body. A spring metal, upper nib 24^a contacts at its rear end with the top 19^a and is formed with a longitudinal slot 31, through which an adjusting bolt 22^a passes, this bolt passing also through the top 19^a. The slot 31 permits longitudinal adjustment of the nib 24^a and by means of the bolt 22^a, said nib may be placed under the desired tension and will be effectively clamped in adjusted position, against the top 19^a.

Whereas, in the form of construction disclosed in Figs. 1 to 5, it is necessary to totally or partially remove the upper nib to fill the reservoir 12, the reservoir 14^a is provided with a filling neck 32 closed by an appropriate cap 33. In Fig. 8, the general proportions of the body 12^b are about the same as in Figs. 1, 2 and 3. The reservoir however, is provided with a top 19^b which extends forwardly into the trough-like portion 13^b to the extent shown by dotted line L. The upper nib 24^b, of resilient nature, rests upon this top wall in the same manner as nib 24^a engages the wall 19^a. This nib is formed with a longitudinal slot 31^b similar to the slot 31, and a clamping and adjusting bolt 22^b passes through this slot and through the top 19^b of the reservoir.

Fig. 10, illustrating an upper, resilient nib 24^c, merely discloses the fact that instead of employing a slot such as 31 or 31^b, a slot 31^c may be employed, having an enlarged end 31^d of a size to receive the nut of the bolt 22^a or 22^b. Thus, when the nib is to be removed, it is simply necessary to loosen this nut and slide said nib until alignment of the enlarged slot end with the nut of the bolt, permits easy removal of the nib, without the necessity of entirely removing the nut from the bolt.

Fig. 11, illustrating a portion of a nib 24^d, illustrates liquid discharge grooves 34 formed in the lower face thereof and positioned as desired, for the purpose of feeding a surplus of ink at one portion or another of the pen, so that shading effects may be readily produced. This detail may be used in connection with any form of construction herein illustrated, and obviously, the nib may be of any desired width, according to the character of the work to be done.

The numerous uses of pens such as that herein disclosed, are too well known to require explanation herein, and it will be obvious to those skilled in the art, that I have produced an exceptionally simple and inexpensive pen, yet one which will be efficient and in every way desirable. As excellent results have been obtained from the general construction disclosed, it is by preference followed. However, within the scope of the invention as claimed, variations may be made.

I claim:

1. A pen comprising an elongated upper nib of resilient material, a pen body having a trough-like portion between whose side walls said nib is received, said body having a substantially flat surface underlying the rear portion of said nib, said surface and said rear portion of the nib converging rearwardly to a point of contact, and means in advance of said point of contact for springing the nib to place it under desired tension, the front end of said nib resting upon and being downwardly turned in front of said trough-like portion of said body.

2. In a pen of the class described, an upper nib comprising an elongated strip of spring metal downwardly turned at one end, and upstanding stiffening flanges on the longitudinal edges of said strip terminating in rear of the front extremity thereof, leaving the front portion of the strip free to flex.

3. A pen of the class described comprising an elongated body of trough-shape in transverse section and provided with a rearwardly opening handle socket at its rear end, the upper side of said socket being downwardly spaced from the upper edges of the body side walls, a transverse bar spanning said side walls, secured thereto and spaced above said upper side of said socket, an elong-

gated upper nib of resilient material, received between said side walls and having its front end turned downwardly in contact with the front end of the bottom of said body, the rear end of said upper nib being interposed between said transverse bar and said upper side of the handle socket, and a clamping screw threaded through said transverse bar for clamping said upper nib against said upper side of said handle 10 socket.

In testimony whereof I have hereunto affixed my signature.

FRANK J. SCHISLER.
